Primary Examiner — Rhea Shields(74) *Attorney, Agent, or Firm* — Eckert Seamans(57) **CLAIM**

The ornamental design for a USB type-C receptacle, as shown and described.

DESCRIPTION

FIG. 1 is an isometric view of a USB type-C receptacle showing our new design;

FIG. 2 is another isometric view of a USB type-C receptacle;

FIG. 3 is a front view thereof;

FIG. 4 is a left side view thereof;

FIG. 5 is a right side view thereof;

FIG. 6 is a back view thereof;

FIG. 7 is a top view thereof; and,

FIG. 8 is a bottom thereof.

In the drawings, the broken lines are for the purpose of illustrating environment only and form no part of the claimed design.

1 Claim, 8 Drawing Sheets
